CLAIM

The ornamental design for an electronic device, as shown and described.

DESCRIPTION

FIG. 1 is a first perspective view of an electronic device, taken from the front.

FIG. 2 is a second perspective view of the electronic device of FIG. 1, taken from the back.

FIG. 3 is a front view of the electronic device of FIG. 1. The unseen portion of the front surface on the base of the electronic device may not be visible during normal use. Therefore, a view disclosing such unseen portion is not included. However, the unseen portion of the front surface on the base of the electronic device is substantially planar and unornamented.

FIG. 4 is a back view of the electronic device of FIG. 1.

FIG. 5 is a left-side view of the electronic device of FIG. 1.

FIG. 6 is a right-side view of the electronic device of FIG. 1.

FIG. 7 is a top view of the electronic device of FIG. 1.

FIG. 8 is a bottom view of the electronic device of FIG. 1; and,

FIG. 9 is a third perspective view of the electronic device of FIG. 1. The third perspective view shows additional broken line subject matter that depicts unclaimed environment of the electronic device which forms no part of the claim.

The broken lines represent features of the electronic device that form no part of the claimed design.

1 Claim, 9 Drawing Sheets
